CLAIM

The ornamental design for a grater or the like, substantially as shown and described.

DESCRIPTION

FIG. 1 is a top perspective view of a grater or the like showing our new design;

FIG. 2 is a bottom perspective view thereof;

FIG. 3 is a side elevational view thereof partially in section and taken along line 3—3 of FIG. 1;

FIG. 4 is a reduced top plan view thereof with only a single grater element illustrated in detail and the location of the remainder thereof located by center line markers;

FIG. 5 is an enlarged view of one form of grater element such taken along circle 5 of FIG. 4;

FIG. 6 is a cross-sectional view of the grater element of FIG. 5 taken along line 6—6 thereof;

FIG. 7 is a reduced bottom plan view thereof;

FIG. 8 is an enlarged view of another of the grater elements taken at circle 8 of FIG. 7;

FIG. 9 is a perspective view of the grater elements taken along line 9—9 of FIG. 8 to depict the relationships thereof;

FIG. 10 is a side elevational view thereof;

FIG. 11 is an end view thereof taken of the handle end; and

FIG. 12 is the other end view thereof.
